UNITED STATES PATENT OFFICE.

HARRY F. STRATTON, OF CLEVELAND, OHIO, ASSIGNOR TO THE ELECTRIC CONTROLLER & MANUFACTURING COMPANY, OF CLEVELAND, OHIO, A CORPORATION OF OHIO.

MEANS FOR PROTECTING SWITCH-CONTACTS UNDER OIL.

1,384,025.

Specification of Letters Patent.

Patented July 5, 1921.

Application filed November 12, 1919. Serial No. 337,591.

To all whom it may concern:

Be it known that I, HARRY F. STRATTON, a citizen of the United States, residing at Cleveland, in the county of Cuyahoga and State of Ohio, have invented new and useful Improvements in Means for Protecting Switch-Contacts Under Oil, of which the following is a specification.

My invention relates to means for protecting switch-contacts under oil.

Butt sliding, or rolling copper contacts are much used for making and breaking heavy electric currents in air. When such switches operate in air part of the wear of their contacting surfaces is due to friction during closing, but most of it is caused probably by the arcing during opening, at which time little globules of copper are formed on the contacts. These globules are detached either by the force of the arc or by the rubbing of the contacts together. Nevertheless, the life of such contacts in air is very great. Although beneficial results have been secured by using butt-contacts in oil, this has been effected at the expense of a decreased operating life of the contacts. Contrary to the case of contacts in air, the heaviest depreciation of contacts in oil occurs during their closing operation. As the flat surfaces of the contacts are approaching each other, they finally touch at some point, the remaining parts of the contact-surfaces being separated by a thin film of oil. At the said point there occurs immediately a very high current density which causes incipient fusion of the copper, and high heating and semi-explosive action of the oil film. Little globules of copper are thrown out sidewise and the entire contacting surfaces become roughened, so that, as the contacts move, one on another, portions of the copper are worn off more rapidly than in the case of contacts opening in air. It is the principal object of this invention to prolong the life of contacts operating under oil.

This I accomplish by providing means whereby some or all of the contacts in oil may be closed before allowing current to pass through them. By so doing the oil film between the contacts is well squeezed out before the current flows, and, as contact has been made at a number of points, no great heating occurs when current begins to flow, and there is not much burning of the oil. Not only is the life of

the contacts greatly increased if they are closed in oil before current flows through them, but their life is also increased by the stoppage of the current before they are opened. My invention is particularly advantageous in systems where it is required to disconnect two or more lines from a source of current supply or from an autotransformer or an equivalent device.

Referring to the accompanying drawings, they show one embodiment of my invention, the parts thereof being shown in three different positions in the three figures.

Figure 1 is a diagrammatic view showing the switch.

Fig. 2 is a similar view showing the switch partly closed.

Fig. 3 shows the switch fully closed.

On Fig. 1 of the drawings, 1 designates a tank containing oil, the level thereof being indicated at 2.

Within the tank 1 and below the oil level 2 is the frame 3 to which the U-shaped core 4 is secured. On the lower leg of the core is the winding 5. 6 is the armature adapted to engage the poles 7 and 8 of the core 4 when the winding 5 is energized. The armature is pivoted to the frame 3 at 10.

The switch lever 11 is pivoted between its ends at 12, one end being pivoted to the armature at 13 and the other end carrying the contacts 14 and 15 insulated from each other.

15' is a second switch lever pivoted at one end to the frame at 16. The link 17 connects the pivot 13 to an intermediate point 18 of the lever 15'. The free end of the lever 15' has the contact 19 adapted to engage with the yielding contact 20. The contacts 21 and 22 are engaged, respectively, by the contacts 14 and 15 and are connected to the supply lines 28 and 29 and the contact 19 is connected to the supply line 30. The contacts 14, 15, and 20 are connected, respectively, to the motor leads 23, 24, and 25 of the alternating motor M, having the stator windings 26 and the rotor 27.

The lines 28, 29 and 30 having been connected to a suitable source of alternating current and the winding 5 having been supplied with current when the parts are as in Fig. 1, the armature 6 moves through the position shown in Fig. 2, at which position the link 17 has brought the contacts 19 and

20 into engagement but the lever 11 has not yet closed the contacts 14, 21, and 15, 22. After the movable parts of my device pass through the positions shown on Fig. 2, they 5 reach the positions shown on Fig. 3 in which the contacts 14, 21 and 15, 22 are closed, and the motor leads 23, 24, and 25 are connected to the supply lines 28, 29, and 30. The spring back of the contact 20 permits the link 17, the armature 6, and the levers 11 and 15' to travel past the positions shown in Fig. 2 to those shown in Fig. 3, in which the contacts 14 and 15 have caused the compression of the springs behind the 15 contacts 21 and 22. When the winding 5 is deenergized the parts all drop back to the positions shown in Fig. 1, passing through the position shown in Fig. 2 where the contacts 14, 21 and 15, 22 are open while 20 the contacts 19 and 20 are still closed.

It is not essential so far as this invention is concerned that all the contacts be under oil. While it is preferred in practice to have all the contacts under oil, my invention could be used if only one pair of contacts, the ones first to close or the last to open, are in oil. The contacts 19 and 20 might readily be made to close last and open first if desired, merely by changing the 30 length of the link 17 and the position of the pivot 12.

While the opening of only the contacts 14, 21 and 15, 22 disconnects the motor from the source of supply, there remains the 35 danger that the wires connected to the contacts 19 and 20 may become grounded and severely shock or injure persons touching any of those wires. Insurance companies require that all the line and transformer 40 switches be opened upon cutting the current supply from the motor. By closing some of the switches first there is economy of power and of structure. The switch closing mag-

net is small and too much work is required of it to close all the switches simultaneously. 45

The principles of my invention may obviously be applied to systems other than that shown. To make the drawing simpler, the motor is shown connected to the lines without the interposition of a transformer, 50 but the principles of this invention are obviously applicable to a motor system employing transformers. In fact, this invention is applicable whenever a plurality of connections between a translating device 55 and a source of current supply, whatever its nature, are either preferably or necessarily made and opened.

I claim:

1. In a circuit controller for multiple conductors, a tank, oil therein, switch-contacts for each conductor, some at least of said contacts being submerged in the oil, and means whereby all the contacts may be closed and whereby some of the submerged 65 contacts close before the remaining contacts close, and whereby some of the submerged contacts may be opened only after the remaining contacts have been opened.

2. In a circuit controller for multiple conductors, a tank, oil therein, a switch for each conductor, at least one of the switches being submerged in the oil, and means for closing all the switches, and for closing some of the submerged switches before the remaining switches may be closed. 75

3. In a circuit controller for multiple conductors, a tank, oil therein, a switch in each line, at least one of the switches being submerged in the oil, and means for closing 80 all the switches, and for opening some of the submerged switches only after the remaining switches have been opened.

Signed at Cleveland, Ohio, this 5th day of November, 1919.

HARRY F. STRATTON.
